CARTON

Perry Belden, Lansdale, Pa., assignor to National Union Radio Corporation, Newark, N. J., a corporation of Delaware

Application October 26, 1943, Serial No. 507,672

7 Claims. (Cl. 229—6)

The present invention relates to a carton designed primarily for the packaging of cathode ray tubes.

Tubes of that character have special uses in apparatus employed extensively by the armed forces, and under such service conditions must meet rigid specifications with respect to the manner and/or form of carton in which they are packed. For reasons of transportation the carton must be compact, light in weight, and most important, the method of suspending the tube within the carton should include an inner supporting member of such design as is not likely to collapse by the absorption of moisture by the material from which said member is made, as for example, paperboard.

A further requirement of a carton adapted to contain a cathode ray tube is that the design of the inner supporting member be such as to accommodate or receive tubes having different geometry. As is well known, tubes of this type have considerable variations in bulb structures respecting length, contour and size of a given bulb. This requires that the construction of the inner supporting member be adapted for such variations without substantial change in design.

It is an object of the present invention to provide a carton having an inner supporting member adapted to afford multiple points of suspension for the contained tube to prevent collapse of the supporting member, particularly by the absorption of moisture.

Another object of the invention is to provide an inner supporting member characterized by structural features which prevent or materially lessen the chances of the tube being damaged by lateral or transversely received blows.

Another object of the invention is the provision of a foldable inner supporting filler that includes sections which makes it unnecessary to use any sort of packing material such as "Kimpak" or the like, in order to protect the top face of the tube from injury and also assist in holding the tube in place when it is sealed within the carton.

A special object is the provision of interlocking fingers on each end of the blank comprising the filler, and having this interlocking means so designed as to permit ready assembly with respect to inserting the opposing fingers.

Other objects will manifest themselves as the description proceeds.

Referring to the accompanying drawing:

Fig. 1 is an extended view or development of the blank forming the inner filler member, con-

stituting the supporting element of a carton embodying the invention;

Fig. 2 is a vertical cross-sectional view of a completely assembled package showing a cathode ray tube supported within the outer container;

Fig. 3 is a similar view taken on line 3—3 of Fig. 2;

Fig. 4 is a perspective view of the inner filler member folded and ready for insertion into the outer container; and

Fig. 5 is a modification of the blank shown in Fig. 1.

The carton illustrated may comprise an outer container 1 having side walls 2 and cut-out closing end flaps 3, the general contour of the container being tubular. An inner supporting filler member referred to generally by the reference character 4 is of a telescopic form and may comprise a one piece blank 5 of paperboard, such as 20 corrugated board. The blank 5 is provided with score lines 6 which form corners in bending and the spacing of the score lines 6 is such as to form sections having different functions. For example, end flaps 7 and 8 are provided with interlocking fingers 9 so as to provide a locking means for holding the blank assembled upon the folding thereof. This feature will be described more particularly hereinafter. Adjacent to the flap 7 is a section 10 which functions as 30 a transverse supporting platform within the container 1. The platform 10 is provided with a circular aperture 11 which acts as a point of suspension for the cathode ray tube 16 when inserted therein.

35 Adjacent to the transverse section 10 is a spacing section 12 which extends to the bottom of the container 1 and functions as one of the side supports. Sections 12 and 13 are adapted to fold in such a manner as to provide an inverted

40 V-shaped support with the apex centrally disposed and said sections of sufficient height with respect to the container 1 that the portion of the tube 16, projecting through an oblong aperture 14, comes into engagement with the edges of

45 sections 12 and 13 just slightly above the beginning of the cylindrical neck portion of said tube. This construction, it will be observed, forms a two point support and also serves as a guide means to maintain the tube in axial alignment 50 with the container 1 and free from the bottom thereof.

Section 8, adjacent to section 13, extends upwardly when the filler member 4 is telescoped within the container 1 to such a point that the 55 bottom edges of the interlocking fingers 9 are in

abutting engagement, with one another, thus completing a side support or wall for the filler 4 and providing means for maintaining the transverse supporting platform 10 in a horizontal position, i. e., at right angle to the side supporting walls of the container 1.

As additional supporting means there are provided laterally extending wings 17 on the outer edges of the platform 10, said wings being adapted to fold upwardly and at an angle with respect to the platform 10. The wings 17 are provided with oblong apertures 18, running longitudinally therewith and positioned relative to the top edge or perimeter of the cathode ray tube so that said edge protrudes or extends slightly through the apertures 18 and thus partially supports the tube along the protruding portions thereof. It will be noted that the width of the wings 17 is such that their opposing end or outer edges adjoin when the wings 17 are folded into position and that the peak formed by these engaging edges of the wings 17 constitute a support for the closing flaps 3 of the container 1. By this arrangement the tube 16 is firmly pressed downwardly and in axial alignment of the container 1.

To afford a safety feature, the outer edges of the sections 12 and 13 may be cut away in any suitable manner, for example, as illustrated by Fig. 5, so that when the sections 12 and 13 are telescoped within the container 1, the portions of the blank 5 immediately adjacent the opposing side walls 2 of the container 1, are out of contact with said side walls. This arrangement thus provides a space between the cut out portions of the edges of the inverted V-shaped support and consequently any blow received transversely at this portion of the carton, will not be transmitted through the apex of said support to the contacting edges of the tube 16 as would be the case if these cut away portions were not provided and the edges of sections 12 and 13 were in direct contact with the side walls 2 of the container 1.

It is obvious that the shape of the cut away edges may take any form but when they are curved as illustrated in Fig. 5 the desired object may be accomplished with a minimum of weakening the strength of the filler member 4 at the point of suspension constituted by the sections 12 and 13 when in folded position.

As an expedient for quickly folding the blank 5, the interlocking fingers 9 may be made of different lengths by cutting the transverse outer edge of the end flaps 7 and 8 at different angles with respect to each other. (See Fig. 5.) By this construction the operative is enabled to more easily insert the fingers 9 in an interlocking relation. It will be noted that although the interlocking fingers will thus vary in length, by having the recesses of the same transverse depth, the height of the supporting wall completed by the engagement of the fingers and their bases resting on the bottoms of the recesses, the supporting platform 10 is maintained at substantially right angle to the walls of the container member.

From the foregoing description it is obvious that the tube 16 is supported at a number of points so that the weight of the tube is distributed among multiple points of suspension thus relieving any excessive strains that might occur if the suspension of the tube consisted of merely a one point suspension, as for example, being suspended only from the circular aperture 11 in the transverse supporting platform 10.

A great advantage realized from this multiple point suspension is the fact that if the material

from which the blank 5 is composed is not very moisture repellent, and the carton is exposed to service conditions of the armed forces, which almost inherently include exposure of the packaged tube to all sorts of weather conditions, absorption of moisture by the filler member does not seriously adversely affect the suspension of the tube because of the distribution of the weight of the tube among the number of points of suspension. In other words, if the tube 16 was supported from a single point of suspension and the filler member absorbed substantial moisture at that point of suspension, the tendency is for the section of the blank 5 forming the point of suspension to fail so that the tube is no longer in proper alignment within the carton and thus easily subject to damage or injury from blows normally received in transportation or storage of the packaged tube.

In the foregoing description and in the claims, I have referred to the material from which the carton is made as "paperboard" and by this term, I mean to include, as generally understood in the trade, all forms of board, such as chip, corrugated, and substitutes therefor, such as fibre. A choice or selection of the kind of paperboard employed will vary with the geometry and size of the tube, but by virtue of the multiple point suspension herein provided, generally speaking, a lighter stock of paperboard may be used for a given tube than would otherwise be possible. Naturally, by being able to lighten the weight of the material used in making the carton, certain economies such as reduction in cost of manufacture, etc., are possible.

Modifications in the construction of my carton will suggest themselves to those skilled in the art, but it is my intention to cover all such modifications as come within the scope of the appended claims.

What is claimed is:

1. A carton for a cathode ray tube comprising an outer container member having side walls and cut-out closing end flaps, an inner supporting filler member of a telescopic form and consisting of a scored blank adapted to form a series of sections when folded along the score lines, one of said sections constituting a transverse supporting platform having laterally extending wing portions provided with die-cut apertures longitudinally arranged with respect to the wing portions, the supporting platform having a die-cut circular aperture, two adjoining sections being adapted to fold into an inverted V-shaped member with the apex of said member extending a substantial distance upwardly from the bottom of the container, the sections forming the inverted V-shaped member having an oblong aperture intersecting a common score line along which said sections are folded, the circular aperture and the oblong aperture being in axial alignment and adapted to engage the contacting surfaces of the tube partially supported therebetween.

2. The construction claimed in claim 1, wherein the wing portions of the transverse supporting platform are designed to furnish support to the tube at the perimeter thereof and also support the folded down closing end flaps of the container.

3. The construction claimed in claim 1, wherein the wing portions of the transverse supporting platform are provided with oblong die-cut apertures longitudinally arranged with respect to said wing portions, said apertures being de-

signed to engage the protruding perimeter of the top part of the tube when the wing portions are folded upwardly and their opposing edges brought into engagement with each other.

4. The construction claimed in claim 1, wherein the opposing edges of the wing portions of the transverse supporting platform when folded into position constitute supporting means for the closure ends.

5. The construction claimed in claim 1, wherein a portion of the outer edges of the sections forming the inverted V-shaped member are cut out so that the apex of said member is spaced a substantial distance from the adjacent side walls of the container.

6. The construction claimed in claim 1, wherein in the end sections of the scored blank have their outer transverse edges provided with interlocking fingers formed by longitudinally arranged recesses dividing the end sections into a plurality 20

of projections having the same transverse depth which is designed to regulate the height of the supporting wall completed by the engagement of the interlacing end sections so that the supporting platform is maintained substantially at right angle to the walls of the container member.

7. The construction claimed in claim 1, wherein in the end sections of the scored blank have their outer transverse edges cut at different angles 10 with respect to each other and provided with interlocking fingers formed by longitudinally arranged recesses dividing the end sections into a plurality of projections having the same transverse depth which is designed to regulate the height of the supporting wall completed by the engagement of the interlacing end sections so 15 that the supporting platform is maintained at substantially right angle to the walls of the container member.
